HEEL PAD

Application filed July 6, 1929. Serial No. 376,420.

This invention relates to heel pads or cushions for use between the heel of the human foot and the inside sole of the shoe or boot.

A primary object of the invention is to

5 provide a cheap, elastic, comfortable, cushion pad of this character to support the weight of the body and relieve it of the jars incident to the walking on hard floors and the like and to correct the tendency to uneven 10 wear on the heel portion of the sole of the shoe or other foot wear.

Another object of the invention is to so construct a pad of this character with a filling 15 the particles of which are free to move in relation to each other thus forming a mobile, plastic, elastic cushion producing the greatest degree of comfort and the particles of which are adapted to accommodate themselves to the conformation of each individual 20 heel thereby counteracting the tendency to an uneven distribution of weight in walking, which is the cause of uneven wear of the heels of shoes and other foot wear.

In carrying out these objects, the invention 25 is susceptible of a wide range of modification without departing from the spirit or sacrificing any of the advantages of the claimed invention; there being shown in the drawings for illustrative purposes a preferred and 30 practical form, in which:

Figure 1 represents a longitudinal section of a section of a shoe with this improved pad shown applied;

Fig. 2 is a transverse section taken on the 35 line 2—2 of Fig. 1; and

Fig. 3 is a perspective view of the pad detached.

The pad or cushion 1 constituting this invention is made in the form of a flat oval 40 sack having a pliable leather upper face 2 for contact with the bottom of the human heel and the other face of which formed of adhesive fabric as shown at 3 which automatically attaches the article to the inside 45 of the shoe. The upper leather facing 2 has an extension 4 at its front end which is designed to provide a tapered connection with the shoe at the shank thereof as shown clearly in Fig. 1 to avoid any objectionable rough 50 place and the edge of this projection or lip

4 is preferably skived along its upper free edge as shown at 5 to more effectively accomplish the flat fitting of the flap against the shoe sole.

These heel pads are of course made to fit 55 the heel as is usual with pads of this character and have the front end cut square across where it extends under the instep. The two faces or fabrics are stitched together around their edges and after they have had the filling 60 inserted therein they are stitched together transversely as shown at 6 to secure a connection for the facing and to hold the filling within the pad.

The pad so formed by the facings 2 and 65 3 is filled loosely or comparatively loosely with a filling composed of dry, finely comminuted cured rubber. The characteristic of this filling is that its particles are free to move in relation to each other forming a mobile, plastic, elastic, cushion which produces the greatest degree of comfort possible and at the same time provides a soft pliable 70 springy pad the free movement of the particles of which adapt it to readily accommodate to the conformation of each individual heel and thereby counteract the tendency of an uneven distribution of weight in walking, removing the cause of the uneven wear on 75 the heels of shoes and other foot wear. This filling which constitutes the gist of the invention provides an entirely elastic and at the same time very soft and pliable pad which absorbs jars more effectively than the pads heretofore used and its finely divided condition makes it readily take on the form and 80 shape of the heel and shoe in a manner that is impossible with material that is permanently formed, molded or compressed into a pad. This material renders it possible for 85 this pad to correct the unequal thrust and push that accompanies peculiarities in gaits and thereby prevent the lateral strains which cause uneven wear on the heel which causes 90 the shoes to "run over."

Without further description it is thought that the features and advantages of the invention will be readily apparent to those skilled in the art, and it will, of course, be understood that changes in the form, propor- 95 100

tion and minor details of construction may be resorted to, without departing from the spirit of the invention or its scope as claimed.

I claim:

- 5 1. An inside heel pad for shoes having a filling of material consisting of small particles of elastic substance capable of changing their relative position under pressure and conforming to the uneven stresses exerted upon them to produce complete freedom from jar and strain.
- 10 2. An inside heel pad having a filling composed of dry, finely comminuted, cured rubber.
- 15 3. A heel cushion composed of disks of pliable leather and fabric arranged in superposed relation and secured together around their edges with a filling between them composed of dry, finely comminuted, cured rubber providing great pliability, elasticity and mobility to the pad, thereby insuring comfort to the wearer.

TOMIZO TANIGAWA.
